UNITED STATES PATENT OFFICE.

HENRY CLAYTON, OF PHILADELPHIA, PENNSYLVANIA.

DESIGN FOR A LEMON-SQUEEZER.

SPECIFICATION forming part of Design No. 18,649, dated October 2, 1888.

Application filed July 14, 1888. Serial No. 279,902. Term of patent 7 years.

To all whom it may concern:

Be it known that I, HENRY CLAYTON, of the city and county of Philadelphia, and State of Pennsylvania, have invented a Design for 5 Lemon Squeezers, of which the following is a specification.

My invention relates to designs for lemon-squeezers; and it consists of certain improvements which are fully set forth in the following specification and illustrated in the drawings which accompany it.

My design is intended for lemon squeezers which are used for small longitudinal sections of lemon, such as quarters or eighths, and consists in giving to the squeezer a spheroidal shape corresponding in form similar to that of the section of the fruit to be used. These small V-shaped pieces of lemon are very frequently used at the present day, and none of the lemon-squeezers in the market are adapted to them. By making the bowl of the squeezer similar in shape to the section of fruit a very convenient instrument is obtained, as well as a pleasing effect.

25 In the drawings, Figure 1 is a side elevation of a lemon-squeezer of my improved design. Fig. 2 is a plan view of the same. Fig. 3 is a sectional elevation of the same through the line *x x* of Fig. 1.

30 The views are deemed necessary to fully illustrate the features of my design.

A and B are two levers, hinged at C and terminating in handles D D, which may be ornamented.

35 E is the expressing bowl or holder for the lemon, which is constructed V-shaped in

cross-section, so that the form corresponds to a longitudinal section of a lemon. This bowl may be either of the full length of a longitudinal lemon section, as shown in Figs. 1 and 2, 40 or it may be only a half-section; but in both of these forms the essential feature of my design is maintained—*i. e.*, the formation of the bowl V-shaped in cross-section to correspond with a cross-section of the longitudinal piece 45 of the lemon; and it is apparent that the mere length of the bowl or lemon-section is not important, as the essential feature of the design remains unchanged.

e e e are a series of holes along the edge of 50 the bowl to allow the expressed lemon-juice to escape.

F is a presser, and I is a foot-rest by which the squeezer may be rested upon a plate.

I construct the edges of the bowl E curved, 55 as shown, thus more nearly corresponding to the shape of the lemon-section.

Having now described my invention, what I claim as new, and desire to secure by Letters Patent, is—

60 The design for a lemon-squeezer herein shown and described, the same comprising the hinged levers A and B, the latter of which is provided with a bowl V-shaped in cross-section corresponding in shape to longitudinal 65 sections of a lemon.

In testimony of which invention I hereunto set my hand.

HENRY CLAYTON.
